CERAMIC SPARK ARRESTER

Joseph P. Richtarsic, Pittsburgh, Pa.

Application January 22, 1949, Serial No. 72,231

2 Claims. (Cl. 183—51)

1

My invention relates to chimney caps and more particularly to screens, caps, and spark arresters for the tops of chimneys for incinerators, homes, apartment buildings, and relatively small industrial chimneys.

Spark arresters, caps and screens for the tops of chimneys are well known in the trade, or art, to which my invention relates, but the short useful life of such screens, spark arresters, etc., is a great annoyance and a considerable expense to the users. When the conventional prior art wire, or cast iron screen is used for an incinerator chimney, then it has been found, that, particularly in some regions, as near salt air and also in large industrial regions where steel mills contaminate the air, a spark arrester may have but one season's use before it crumbles away in powder and flakes of a compound of the metal of which the spark arrester is made. In other regions the useful life is only a little better.

Some of the broad objects of my invention are the provision of chimney spark arresters of permanence, reliability, low cost, and artistic appeal.

Other objects of my invention are the provision of efficient and economical chimney tops that provide protection against the hazards of fire and which are made of ceramic material which neither rusts nor corrodes.

A specific object of my invention is to provide a chimney cap of a one-piece sleeve of firebrick in the shape of a screen with a lid for the sleeve of similar material and also in the form of a screen.

Another specific object of my invention is the provision of clay, or ceramic, chimney caps each including a portion that is a continuation of the firebrick type of liner for a chimney but perforated with many perforations and extending above the chimney brick work, and each such continuation being provided with a foraminous lid of firebrick and constructed to loosely interlock with the extension.

Another specific object of my invention is the provision of foraminous ceramic spark arresters for chimneys provided with means for catching the fly-ash that may form at the chimney cap during use.

The recited objects are merely illustrative. Other objects and advantages will become more apparent from a study of the following specification and the accompanying drawings, in which:

Figure 1 is a perspective view of a preferred embodiment of my invention;

Fig. 2 is a perspective view of a modification of my invention;

2

Figs. 3 and 4 are perspective views of what might be termed the more artistic types of spark arresters embodying my invention; and

Fig. 5 is a perspective view of the preferred embodiment of my invention provided with additional protective features for catching sparks and fly-ash.

Referring to Fig. 1 the sleeve 1 designates a ceramic member preferably of a firebrick type of construction. In the preferred construction this member, or sleeve, 1 is in length and horizontal sectional dimensions exactly like the usual flue liners put in chimneys.

This sleeve 1 is disposed in axial alignment with the top-most section of flue liner and thus forms a continuation of the liner. The disposition of the lower end of the sleeve 1 with reference to the chimney top 2 is such that it extends one inch to three inches below the top horizontal surface 3 of the top layer of bricks 4.

To firmly secure the sleeve 1, having the square horizontal sectional dimension, into the chimney top, I use a suitable layer of mortar, or cement 5, on the top layer of bricks and in addition add the bead, or sloping filler layer, 6 next to the sleeve 1 and inner top edge of the top bricks.

The top edge of the sleeve 1 is provided with three rectangular notches 7, 8 and 9. To make certain that sparks have no direct exit, I provide a ceramic lid 10 for the sleeve 1. The lid is provided with the lugs, or rectangular projections 11, 12 and 13 to fit loosely into the notches 7, 8 and 9, respectively. I thus select three points of support so that wind and storms do not effect an oscillation of the lid 10 on the sleeve end, as would be the case if four supports were provided. If wind can cause tapping of the parts against each other, the lid 10 and possibly the sleeve 1, or both, may be broken.

To obtain a free flow of the smoke from the chimney, I provide the terra cotta, or clay, parts 1 and 10 with the perforations shown. The number and size of the perforations, or holes is so chosen that the strength of the sleeve is not materially affected and the total sectional area is equal to, but preferably greater than, the sectional area of the flue liner.

In the showing in Fig. 2, the chimney 22 is provided with the cement covering 25 and bead 26 for holding the sleeve 21. These elements are in construction and function exactly like the corresponding elements mentioned in connection with the discussion of Fig. 1, except that the upper end of the sleeve 21 is not provided with notches for receiving the lid 23. The lid 23 is depressed cen-

trally at 24, thus having the general shape of a serving tray or may be provided with several downwardly projecting lugs adjacent the internal corners of the side walls. These lugs may be somewhat similar to the lugs 47 and 48 shown in Fig. 4. The sleeve 21 and lid 23 are provided with many circular openings to thus provide a spark arrester for the chimney 22.

In the showing in Fig. 3, the sleeve 31 has the same general construction as the sleeve shown in Figs. 1 and 2, except that the front edge is slightly lower and the three remaining upper edges are provided with a groove 32 for receiving the rib 33 of the generally semi-cylindrical lid 34.

The front edge of the lid 34 is provided with the strengthening rib 35 having the special aperture 36 for receiving a ceramic plug to lock the lid 34 in position on the sleeve 31. The sleeve 31 and lid 34 are provided with enough openings of an appropriate size that the total sectional area of the openings is greater than the sectional area of the flue liner.

In the showing in Fig. 4, the chimney 42 holds the sleeve 41 by means of the cement 45 and bead 46. The sleeve 41 is, however, cylindrical.

The upper edge of the sleeve 41 is provided with a strengthening rib 43 having an inwardly directed overhanging lip. The lip is provided with two notches, as notches 44. These notches are so disposed that the lugs 47 and 48 may be passed freely through the notches 44.

The lugs 47 and 48 are on the under inner edge of the dome-shaped perforated lid 49. When the lid 49 is placed on the sleeve so that the lugs 47 and 48 pass freely through the notches 44, then the lid may be merely turned through a small angle to latch the lid on the sleeve 41.

In the showing in Fig. 5, the spark arrester screen proper comprises an elongated sleeve-like screen 51 mounted on the chimney top and secured by the cement 55 and the bead 56.

A second sleeve 61 surrounds the first sleeve 51 so that a considerable space is provided between the two sleeves. A third retaining sleeve 71 is, for almost half the length of the sleeve 61, disposed about the lower portion of sleeve 61 and is cemented to it, so that sleeve 61 is firmly held on the chimney top.

The sleeves 61 and 71 are provided with registering openings 72 and 73 in each face at the base and directly above the cement 55. Fly-ash that forms at the perforations of the sleeve 51 thus falls down in the space between the sleeves

51 and 61 and may from time to time be removed, or cleaned out.

The sleeve 61 is provided with one or more rings of perforations as 62 and 63 directly above the end of sleeve 71 and in registry or preferably slightly below the lowest row of perforations in the sleeve 51. The perforations 62 and 63 aid in giving the desired draft through the space between the sleeves so that the smoke from the chimney may pass freely from the sleeve 51 but no fly-ash gets out of the space between the sleeves 51 and 61, while not at rest while the chimney is in use, circulates upon itself so much that the burning embers, should any get out of the sleeve 51, which is only seldom, are arrested by sleeve 61.

While I have shown and described but a few embodiments of my invention, I do not wish to be limited to the particular showings made but wish to be limited only by the scope of the claims here-to appended.

I claim as my invention:

1. A spark arrester for the top of a chimney, comprising, in combination, a ceramic foraminous sleeve, in shape and length generally like the rectangular flue liner lengths in common use, having its bottom end cemented to the top of the chimney, a square ceramic foraminous lid for the top of the sleeve, said lid being provided with lugs cooperating with the top edge of the sleeve to interlock the lid and top end of the sleeve to thus hold the lid in position on the sleeve.

2. A spark arrester for the top of a chimney, comprising, in combination, a ceramic foraminous sleeve, square in sectional area and having generally the length of the flue liner lengths in common use, secured to the top of the chimney, a plurality of notches in the upper end of the sleeve, a foraminous ceramic generally square lid for the sleeve having lugs adapted to be disposed in said notches to retain the lid on the sleeve.

JOSEPH P. RICHTARSIC.
